Thomas Howe ATTORNEY

UNITED STATES PATENT OFFICE.

ALAN M. BENNETT, OF WESTFIELD, NEW JERSEY, ASSIGNEE, BY MESNE ASSIGNMENTS, TO BURKE ELECTRIC COMPANY.

ARC-WELDING SYSTEM.

1,357,486.

Specification of Letters Patent. Patented Nov. 2, 1920.

Application filed March 29, 1918. Serial No. 225,425.

To all whom it may concern:

Be it known that I, ALAN M. BENNETT, a citizen of the United States, residing at Westfield, county of Union, and State of New Jersey, have invented new and useful Improvements in Arc-Welding Systems, of which the following is a specification.

This invention relates to means for welding, brazing or repairing metals by means of the electric arc.

The main object of the invention is to provide simplified means for controlling the current in an arc welding system. It contemplates the employment and control of a resistance in the working circuit such that the current in the welding circuit will be desirably controlled but without the inefficiency which has previously characterized systems wherein the working currents were caused to traverse resistances.

Other and ancillary objects of the invention will appear hereinafter.

The accompanying drawing, which illustrates the invention, is a diagram setting forth an electric arc welding system embodying the invention.

Referring to the drawings, the apparatus comprises a direct current generator including an armature 1, a separately excited field 2, which may receive its energy from any suitable source of direct current, and a series field 3 of which the magnetomotive force opposes that of the field 2.

The work circuit may be traced from one side of the armature 1 through the series field 3, conductor 4, resistance 5 and conductor 6 to the work 7 which forms one electrode of the arc. Thence the circuit passes across the arc to the movable electrode 8, through the conductor 9, the coil of the relay 10 and the conductor 11 to the other terminal of the armature.

When the relay 10 is energized its contacts close a circuit through the coil of the relay 12 between the conductors 6 and 9; that is, across the terminals of the arc, so that the coil of the relay 12 is energized proportionately to the voltage across the arc. Since the coil of the relay 10 is in series in the work circuit the coil of relay 12 will have its circuit closed only when current is flowing in the work circuit.

A short circuiting shunt for the resistance 5, comprising the conductors 13 and 14, is

adapted to be closed by the contacts of the relay 12 when the relay is energized.

When the apparatus is not working the parts will be in the positions indicated on the drawing. The voltage of the generator will be that due to the field 2. There being no current in the work circuit, the series field will not be energized and there will be no drop of potential from the generator to the arc electrodes. If now the movable electrode be struck against the work to initiate the arc current will flow in the work circuit. Excessive rush of current however will be prevented by the series field 3, which cuts down the generator voltage, and the resistance 5. The relay 10 being energized by the current in the work circuit, its contacts will be closed, closing the circuit of the coil of the relay 12 across the electrodes. When the electrode 8 has been removed from the work and the arc drawn, the drop of potential across it will energize the relay 12 causing its contacts to close and short circuiting the resistance 5. The arc will then operate at substantially the voltage of the generator, the generator being so constructed and arranged that the excitation of the field 2 opposed by that of the series field with normal working current will produce the desired arc voltage while variations in arc current will affect the generator voltage so that the variation will be substantially neutralized and the current maintained substantially constant.

While the invention has been illustrated in what is considered its best application, it may have other embodiments without departing from its spirit and is not therefore, limited to the structure shown in the drawing.

What I claim is—

1. In a system for welding, repairing and otherwise treating metals by the electric arc, the combination with a generator, having an exciting field and a series field opposed thereto, for impressing voltage on the circuit, of electrodes, a resistance, conductors connecting said electrodes, generator and resistance in circuit and means for removing said resistance from said circuit.

2. In a system for welding, repairing and otherwise treating metals by the electric arc, the combination with a generator, having an exciting field and a series field opposed

thereto, for impressing voltage on the circuit, of electrodes, a resistance, conductors connecting said electrodes, generator and resistance in circuit and means controlled by 5 the arc voltage for removing said resistance from said circuit.

3. In a system for welding, repairing and otherwise treating metals by the electric arc, the combination with a generator, having 10 an exciting field and a series field opposed thereto, for impressing voltage on the circuit, of electrodes, a resistance, conductors connecting said electrodes, generator and resistance in circuit and means controlled by 15 the working current for removing said resistance from said circuit.

4. In a system for welding, repairing and otherwise treating metals by the electric arc, the combination with a generator, having an 20 exciting field and a series field opposed thereto, for impressing voltage on the circuit, of electrodes, a resistance, conductors connecting said electrodes, generator and resistance in circuit and means controlled by 25 the arc voltage and working current for removing said resistance from said circuit.

5. In a system for welding, repairing and otherwise treating metals by the electric arc, the combination with a generator for impressing voltage on the circuit, of electrodes, 30 a resistance, conductors connecting said electrodes, generator and resistance in circuit and means operated on failure of arc voltage on short circuit and controlled by 35 the working current for removing said resistance only from said circuit.

6. In a system for welding, repairing and otherwise treating metals by the electric arc, the combination with a generator for impressing voltage on the circuit, of electrodes, 40 a resistance, conductors connecting said electrodes, generator and resistance in circuit and means operated upon failure of the arc voltage on short circuit and controlled by 45 the working current for establishing a shunt connection from one terminal of said resistance to the other.

7. In a system for welding, repairing and otherwise treating metals by the electric arc, 50 the combination with a generator, having an exciting field and a series field opposed thereto, for impressing voltage on the circuit, of electrodes, a resistance, conductors connecting said electrodes, generator and resistance in circuit, a shunt for said resistance and a relay comprising contacts in said 55 shunt and having its coil connected across the arc.

8. In a system for welding, repairing and otherwise treating metals by the electric arc, 60 the combination with a generator, having an

exciting field and a series field opposed thereto, for impressing voltage on the circuit, of electrodes, a resistance, conductors connecting said electrodes, generator and resistance in circuit, a shunt for said resistance, a relay comprising contacts in said shunt and having its coil connected across the arc, and a relay having its coil in the work circuit and contacts in the circuit of the coil of the coil of the aforesaid relay.

9. In a system for welding, repairing and otherwise treating metals by the electric arc, the combination with a generator, for impressing voltage on the circuit, of electrodes, 75 a resistance, conductors connecting said electrodes, generator and resistance in circuit, a shunt for said resistance connected at its ends to the terminals of said resistance, a relay comprising contacts in said shunt and having its coil connected across the arc, and a relay having its coil in the work circuit and contacts in the circuit of the coil of the aforesaid relay.

10. In a system for welding, repairing and otherwise treating metals by the electric arc, the combination with a generator for impressing voltage on the circuit, of electrodes, a resistance, conductors connecting said electrodes, generator and resistance in circuit, 90 means for removing said resistance from the circuit comprising a relay energized according to the arc voltage and a relay controlling the circuit of the aforesaid relay.

11. In a system for welding, repairing and otherwise treating metals by the electric arc, the combination with a generator for impressing voltage on the circuit, of electrodes, a resistance, conductors connecting said electrodes, generator and resistance in circuit, 100 means for removing said resistance from the circuit comprising a relay energized according to the arc voltage and a relay controlled according to the working circuit controlling the circuit of the aforesaid relay.

12. In a system for welding, repairing and otherwise treating metals by the electric arc, the combination with a generator for impressing voltage on the circuit, of electrodes, a resistance, conductors connecting said electrodes, generator and resistance in circuit, a normally opened shunt for said resistance, a normally opened relay having its contacts in said shunt and adapted to be connected across the arc and a second normally opened relay having its normally opened contacts in the circuit of the coil of the aforesaid relay and having its coil connected in series in the work circuit.

In testimony whereof I have signed this 120 specification this 16th day of March, 1918.

ALAN M. BENNETT.
